INVENTOR.

UNITED STATES PATENT OFFICE

124,448

DESIGN FOR A DINNER DRESS ENSEMBLE OR SIMILAR ARTICLE

Karen Stark, New York, N. Y.

Application September 21, 1940, Serial No. 95,251

Term of patent 3½ years

To all whom it may concern:

Be it known that I, Karen Stark, a citizen of the United States, residing at Hyde Park Hotel, New York city, in the county of New York and State of New York, have invented a new, original, and ornamental Design for a Dinner Dress Ensemble or Similar Article, of which the following is a specification, reference being had to the accompanying drawing, forming part thereof.

I claim:

The ornamental design for a dinner dress ensemble or similar article, substantially as shown.

KAREN STARK.
